United States Patent Office

Des. 204,587
Patented Apr. 26, 1966

204,587

FAUCET SPOUT

William H. Armstrong, Bloomfield Hills, Mich., assignor to Borg-Warner Corporation, a corporation of Illinois

Filed July 19, 1965, Ser. No. 86,199

Term of patent 14 years

(Cl. D91—3)

Fig. 1

I claim:

The ornamental design for a faucet spout, substantially as shown.
